(57) **CLAIM**

The ornamental design for an mandibular advancement device with comfort bumps, as shown and described.

DESCRIPTION

FIG. 1 is a top perspective view of the presently disclosed mandibular advancement device with comfort bumps.

FIG. 2 is a bottom perspective view of the presently disclosed mandibular advancement device with comfort bumps.

FIG. 3 is a front view of the presently disclosed mandibular advancement device with comfort bumps.

FIG. 4 is a back view of the presently disclosed mandibular advancement device with comfort bumps.

FIG. 5 is a right side view of the presently disclosed mandibular advancement device with comfort bumps.

FIG. 6 is a left side view of the presently disclosed mandibular advancement device with comfort bumps.

FIG. 7 is a top view of the presently disclosed mandibular advancement device with comfort bumps; and,

FIG. 8 is a bottom view of the presently disclosed mandibular advancement device with comfort bumps.

The broken line in the drawings is included for the purpose of illustrating portions of the mandibular advancement device with comfort bumps and forms no part of the claimed design.
